CENTER FORK STOP MOTION FOR LOOMS

Application filed June 15, 1931. Serial No. 544,377.

This invention relates to looms and is more particularly directed to a filling stop mechanism of the type which utilizes a center filling fork mounted on the lay.

5 It is now the ordinary practice in the so-called "center fork" stop mechanism for looms to provide a detector mounted upon the lay between the ends thereof and to cause such filling fork or detector to be raised periodically to permit the shuttle to pass and then to feel for the filling and detect its presence or absence in the shed. Should the filling be absent on any pick, it is desirable that the filling fork will initiate the operation of a train 10 of mechanism to effect the loom stoppage.

One of the objects of the present invention is to provide a center fork stop motion for looms wherein detection of presence or absence of filling in the shed may be ascertained 20 on each pick of the shuttle, and upon detection of filling absence set in operation a train of mechanism for effecting loom stoppage.

In the practical operation of looms of the center fork type, the filling laid in the shed 25 will frequently not support the tines of the center fork or detector following loom stoppage, with the result that the loom may again be stopped unnecessarily.

It is a further object of the invention, therefore, to provide means which will serve to prevent loom stoppage on the first beat up movement of the lay when the loom is started after having been stopped.

It is desirable that the time intervals of the 35 center fork movements be so coordinated that the shuttle may get out of the shed before the fork completes its detecting function, and another important feature of the present invention consists in providing means whereby 40 the time interval for raising the center fork is different or shorter than the time interval of lowering the fork to determine the presence or absence of filling in the shed.

Various other features of the invention and 45 novel combinations of parts will best be made clear from the following description and accompanying drawings of one good form thereof.

In the drawings:—

50 Fig. 1 is a perspective view of portions of

a loom provided with the present invention, some of the parts being broken away;

Fig. 2 is a front view of the lay showing features of the present invention and with portions of the lay broken away;

Fig. 3 is an under perspective view of the knock-off plunger and its associated parts, portions being broken away;

Fig. 4 is a detail in front elevation showing the cam means for raising the center 60 fork and for effecting loom stoppage should the center fork fail to detect presence of filling in the shed.

Fig. 5 is a detached detail partly in section;

Fig. 6 is a side elevation partly in section 65 showing the filling fork controlling mechanism for effecting different time intervals in the center fork movements; and

Fig. 7 is an enlarged side elevation of the cam for effecting movement of the center 70 fork.

The loom frame 1 may be of usual construction and provided with the lay 2 which is supported by the usual lay swords 3, only one of which is shown, for rocking or beat up 75 movements. The lay 2 is provided with the usual reed 4 and about central of the lay there is a recess 5 above which the filling thread *a* is laid on each pick of the shuttle. This general relation of the parts is shown 80 in Fig. 1 wherein the shuttle 6 is shown as in the left hand box.

Mounted on the lay substantially central thereof is a bracket 7 having the frontwardly projecting portion 8 between the sides of 85 which is a rocking carrier 9 to which the tines 10 of the center fork are secured.

The axis of the rocking carrier 9 may extend to one side of the bracket, as at 11, and connected with the extension 11 is a light 90 spring 12, which serves to impart to the tines of the center fork a downward movement for ascertaining whether filling has been laid in the shed or not.

In accordance with the present invention 95 the center filling fork is associated with a bunter mounted on the lay and so related to a knock-off plunger that when the filling fork detects absence of filling in the shed the bunter will be positioned to engage the 100

knock-off plunger and through a connected train of mechanism effect loom stoppage.

- In the present instance of the invention the lay 2 has secured on its front face a bracket 5 13 to which is pivotally connected at 14 the bunter 15. As shown, the bunter 15 is carried on one arm of a bell crank lever and extends frontwardly therefrom, as more clearly indicated in Fig. 1. One arm 16 of the bell crank 10 lever carries the bunter 15 and the heel portion 17 projects rearwardly from the arm 16 of the bell crank lever and rests upon the surface of the bracket 13 to thereby take up the shock incident to engagement of the bunter 15 with the knock-off plunger, as will more 15 fully appear. The other arm 18 of the bell crank lever extends in the path of a pin 19 adjustably secured to the actuating rod 20 whose lower end passes through a guide 21 20 secured to the lay sword, as more clearly indicated in Fig. 1. Pivotally mounted on a bracket 22 supported from the loom frame is a lever 23, its pivotal point 24 being located between the ends of the lever and the forward end of lever 23 has a pin and slot 25 connection 25 with the actuating rod.
- The rearwardly extending arm 26 of the lever bears against a cam 27 secured to and operated by the under cam shaft 28.
- It is desirable that the detection of presence 30 or absence of filling in the shed be made on each pick of the shuttle and consequently the cam 27 is shown as a two lobe cam, it being understood that the under or cam shaft 28 35 makes one revolution to each two revolutions of the crank shaft which operates the lay, as usual. From the construction thus far described it would be apparent that the bunter 15 will be moved lengthwise of the lay in one 40 direction and in order that it may be returned or given movement lengthwise of the lay in the opposite direction a spring 29 is caused to act upon the bell crank lever, as indicated in Figs. 1 and 2, that is to say, one end of the 45 spring is connected to the arm 16 of the bell crank at 30, as shown, and the other end of the spring is connected to a fixed member preferably extending from the bracket 13, as at 31, thus when the bunter 15 has been moved in one direction by the actuating cam and connections, as described, and the lower part of the cam is presented to the arm 26 of the lever 23, the spring will act upon the bell 50 crank to move the bunter yieldingly in the opposite direction. It may be desirable in some instances to provide a stop for limiting the movement of the bunter 15 longitudinally of the lay and to this end the bracket 13 is provided with the stops 32. A rod 33 is connected at 34 with the arm 16 of the bell crank and extends longitudinally of the lay where its opposite end is supported in a bearing carried by the bracket 7. The bearing 35 60 formed by the bracket 7 therefore acts as a

guide for guiding the rod 33 in its movements induced by the bell crank.

Secured to the rod 33 is a cam member 36 having the cam portions 37 and 38 between which and preferably where the two cam portions join there is formed a shoulder or notch 39. The cam member 36 may be secured to the rod 33, adjustably if desired, by means of the set screws 40.

Extending laterally from the axis of the center fork is a stop finger 41 which, of course, moves in consonance with the center fork. When the bunter 15 is moved longitudinally of the lay by its actuating cam the stop finger 41 will ride along the inclined surfaces 37, 38 of the cam member 36, thereby lifting the tines of the center fork to permit the shuttle to pass, and as indicated in the drawings, such operation is effected on movement of the cam 36 to the left, Figs. 2 and 4. As the bunter 15 is moved to the right under the action of the spring 29, the tines of the center fork will drop under the influence of gravity plus the impulse of the spring 12 and if filling has been laid in the shed the tines of the center fork will take position, as indicated in Fig. 1. If, however, no filling is laid in the shed the tines of the fork will not be arrested by the filling and will drop into the recess 5 of the lay, thereby causing the stop finger 41 to ride down the incline 38 of the cam member 36 and engage with the stop shoulder 39 and stop movement of the bunter 15 in position to cause loom stoppage, as will presently appear.

It will thus be seen that the bunter 15 is given a positive movement in one direction by the cam actuated means to pass the bunter in front of the knock-off plunger and into an inoperative position relative thereto, but as the bunter is moved in the opposite direction by its spring and filling is absent, the bunter will be arrested in operative relation to the knock-off plunger, so that on frontward movement of the lay the loom will be stopped.

The breast beam 42 has a side portion 43 for the support of the knock-off plunger and its associated parts, as shown in Fig. 1.

The knock-off plunger 44 has a downwardly extending arm 45 preferably provided with a notch 46 for engagement by the bunter when the filling is absent from the shed. The knock-off plunger 44 extends frontwardly and is connected at 47 with a knock-off lever 48, which is pivotally mounted on the support 43 at 49 and its opposite end bears against the shipper 50, the result being that should the knock-off plunger be moved frontwardly by the bunter the shipper will be detached from its holding notch and loom stoppage result.

The knock-off plunger 44 has a slide 51 mounted thereon, which slide is normally under the impulse of a spring 52, normally

acting to hold the slide in rear position with respect to the knock-off plunger, a position which is determined by the end of the slide contacting with the shoulder portion 53 of the downwardly extending arm 45.

Extending from the slide 51 is a cam projection 54 which, when the knock-off plunger and slide are moved frontwardly to effect loom stoppage, rides on to a bridge 55 formed as part of the bracket 56, the effect being that on such forward movement of the knock-off plunger and slide the arm 45 of the plunger will be raised out of the path of the bunter and simultaneously therewith the loom will be stopped.

On the first forward beat of the lay following loom stoppage the filling may not be laid in the shed under sufficient tension to support the tines of the center fork and in the absence of means to prevent it, the loom would be again stopped.

In accordance with the present invention, however, means are provided for locking the knock-off plunger in an inoperative position relative to the bunter 15 and maintain it in such inoperative position until after the first forward beat of the lay following loom stoppage and thereupon freeing the knock-off plunger for movement to operative position, so that on the pick of the shuttle following loom stoppage the knock-off plunger is in position to be actuated by the bunter provided filling fails.

Pivottally mounted on the support 43 at 57 is a locking member or lever 58, one end of which is connected to the slot 51 by the slide and pin connection 59, best shown in Fig. 3.

The opposite end of the locking member or lever 58 extends beyond the pivotal support 57, as indicated at 60, and during normal weaving operations a latch 61 rests upon the top portion 60 of the lever 58.

The latch 61 is pivotally mounted at 62 and has a downwardly extending trip finger 63 positioned in the path of a trip member 64 mounted on the lay by means of a bracket 65, as indicated in Fig. 1.

The latch 61 is normally under the influence of a spring 66, one end of which may be conveniently connected to the shipper knock-off lever 48 and the other end of which is attached to the latch at 67, and consequently exerts a downward pull upon the latch. During normal weaving operations the trip finger 63 and the trip member 64 will not engage by reason of the fact that the finger 63 is supported in a frontward position by the engagement of the latch upon the end of the locking member or lever 60. When, however, the loom is stopped by absence of filling and the knock-off plunger is moved frontwardly the end 60 of the locking member or lever 58 will pass to the rear of the end of the latch 61, whereupon the lever

will be locked and the finger 63 be presented in sufficient rearward position for engagement by the member 64 on the lay.

During weaving when filling is regularly laid in the shed the parts occupy the position, as indicated in Fig. 1. Should the filling fail to be laid in the shed the center fork will indicate that fact and the bunter 15 be stopped in operative relation with the end of the arm 45 of the knock-off plunger, so that on forward movement of the lay the knock-off plunger and the slide 51 thereon will be moved frontwardly, thereby knocking off the shipper and positioning the end 60 of the locking member or the lever 58 rearwardly of the latch 61 which will thereupon hold the slide 51 in locked position with the plunger knock-off in an inoperative position. When the loom is first started after having been stopped the knock-off plunger and bunter are inoperatively related. As the lay completes its forward movement for the beat-up following loom stoppage, the trip member 64 will strike the downwardly extending trip finger 63 of the latch and free the slide 51 for movement rearwardly under the impulse of the spring 52, thereby again positioning the knock-off plunger for engagement by the bunter should filling fail on any succeeding beat up of the lay.

Owing to the fact that the arm 45 of the knock-off plunger extends downwardly the stress of the bunter thereagainst will have a tendency to lift the forward end of the plunger where it is connected to the knock-off lever 48 and so it may be desirable in some cases to interpose a spring 68 between the end of the knock-off lever 48 and the front end of the plunger as indicated in Fig. 3, but this may not always be necessary.

It may be desirable in some cases to provide a guard to prevent undue upward movement of the stop finger 41 which is connected to the center fork and this is readily provided by means of a fixed guard member 69, which overlies the end portion of the stop finger 41.

In order to insure that the trip finger 63 of the latch 61 may not be struck by the trip member 64 during normal weaving operations, the top surface of the locking member or lever 60 is inclined upwardly towards the rear of the loom, Fig. 5, to provide a camming surface which acts to lift the front end of the latch 61 as the end 60 of locking member or lever 58 moves frontwardly upon being released by the latch, thus moving the trip finger 63 further frontwardly so that it will not be engaged by trip member 64.

As hereinbefore stated the present invention provides for effecting a rapid upward movement of the center fork followed by a slower downward movement until the protection point has been reached and then a rapid drop provided there is absence of fill.

ing. This enables the center fork to be delayed somewhat in its downward movement, and then to approach the detecting point and engage the filling without injurious effect thereon, and then in case filling is absent to suddenly drop to position the parts for loom stoppage.

8 The lower or cam shaft 28 carries the cam 27 which is of the two lobe type to effect detection of filling on each pick of the shuttle. As indicated more clearly in Figs. 6 and 7, the cam 27 has portions between the points *b* and *c* which act through the lever 23 to cause rapid upward movement of the center 10 fork to permit the shuttle to pass, and a portion between the points *c*, *d* for permitting the center fork to drop slowly to the protection point and a portion between the points *d* and *e* to permit sudden drop of the center 15 fork should filling be absent from the shed.

10 The forward end of the lever 23 is under the influence of a spring 65, one end of which may be secured to the lever 23, as indicated in Figs. 1 and 6, and the other end of which 20 may be conveniently secured to the lay rock shaft 66, the function of such spring being so cause the rear end portion of the lever 23 to bear against the periphery of the cam 27. The spring 65 is preferably stronger than the 25 spring 29, the function of the latter being primarily to cause the lever arm 18 to bear upon the pin 19 of the actuating rod 20.

15 The time interval relation in the movements of the center fork are peculiarly advantageous in some looms, particularly where the loom is provided with a loose reed motion, as it enables the shuttle to pass out of the shed before the detecting function of the center fork has been completed.

20 What is claimed is:

1. In a center fork stop motion for looms, the combination of the lay, a bunter mounted on the lay for movement relative thereto, a cam, and connections between the cam and 25 bunter for moving the bunter longitudinally of the lay in one direction, a spring for moving the bunter longitudinally of the lay in the opposite direction, a center fork mounted on the lay, a longitudinally movable link connected to the bunter for movement thereby and supporting a cam member bodily movable longitudinally of the lay with the link for raising the center fork as the bunter is moved by its actuating cam in one direction, 30 and interlocking means between the center fork and movable link for arresting movement of the bunter by the spring when filling fails to be laid in the shed.

2. In a center fork stop motion for looms, 35 the combination of the lay, a bunter pivotally mounted on the lay for movement longitudinally thereof, an under or cam shaft having a cam, connections between the cam and bunter for swinging the bunter longitudinally of the lay in one direction, a spring for swinging the

40 bunter longitudinally of the lay in the opposite direction, a center fork mounted on the lay for detecting the presence or absence of filling in the shed, a rod connected to the bunter for movement thereby, a cam member supported by and bodily movable with the rod for raising the center fork and then freeing it to the exercise of its detecting function, interengaging devices between the cam member and center fork for arresting the 45 movement of the rod under the stress of the spring should the fork detect absence of filling, and means actuated by the bunter to effect loom stoppage when the bunter is operatively positioned.

45 3. In a center fork stop motion for looms, the combination of the lay, a center fork mounted on the lay, a bunter pivotally connected to the lay for swinging movement longitudinally thereof, an under or cam shaft 50 having a cam for causing movement of the bunter about its pivotal connection with the lay in one direction longitudinally thereof, a spring for moving the bunter longitudinally of the lay in the opposite direction, a rod connected to the bunter for movement thereby, a cam device connected to the rod for raising the center fork as the bunter is swung about its pivot by its actuating cam and a locking 55 notch formed in the cam device, an arm actuated by the center fork for engagement with said locking notch when the center fork detects absence of filling in the shed, and a knock-off plunger actuated by the bunter to stop the loom when the bunter is arrested in its movement.

50 4. In a center fork stop motion for looms, the combination of the lay, a center fork mounted on the lay, a bunter pivotally connected to the lay, stops for limiting the swinging movement of the bunter, an under or cam shaft having a cam for causing movement of the bunter about its pivotal connection with the lay in one direction longitudinally of the lay, a spring for moving the bunter longitudinally of the lay, in the opposite direction, a rod supported on the bunter for movement thereby, a cam device connected to the rod for raising the center fork as the bunter is swung about its pivot by its actuating cam and a locking notch formed in the cam device, an arm actuated by the center fork for engagement with said locking notch when the center fork detects absence of filling in the shed, and a knock-off plunger actuated by the bunter to stop the loom when the bunter is arrested in its movement.

55 5. In a center fork stop motion for looms, the combination of the lay, a bunter mounted on the lay for movement lengthwise of the lay and having a heel bearing against the lay to resist the shock of knock-off, an under or cam shaft having a cam for moving the bunter lengthwise of the lay in one direction, a spring for moving the bunter longitudinal- 60

ly of the lay in the opposite direction, a center fork, means between the center fork and bunter for locking the bunter from movement by the spring when the center fork detects absence of filling in the shed, and means for engagement by the bunter to effect loom stoppage when the center fork detects absence of filling in the shed.

6. In a center fork stop motion for looms, 10 the combination of the lay, a center fork, a bunter mounted on the lay and controlled in its position by the center fork, a plunger knock-off adapted to be actuated by the bunter when the center fork detects absence 15 of filling in the shed, a lock for holding the plunger in an inoperative position after loom stoppage, and a trip for the lock actuated on the first beat-up movement of the lay after loom stoppage to permit the knock-off plunger 20 to move to operative position.

7. In a center fork stop motion for looms, 25 the combination of the lay, a center fork, a bunter mounted on the lay and controlled in its position by the center fork, a plunger knock-off adapted to be actuated by the bunter when the center fork detects absence 30 of filling in the shed, a spring controlled lock for holding the plunger in an inoperative position after loom stoppage, and a trip for the lock actuated on the first beat-up movement 35 of the lay after loom stoppage to permit the knock-off plunger to move to operative position.

8. In a center fork stop motion for looms, 40 the combination of the lay, a bunter mounted on the lay, a cam for moving the bunter in one direction, a spring for moving the bunter in the opposite direction, a center fork acting to arrest movement of the bunter under the stress of the spring when the fork 45 detects absence of filling, a knock-off plunger normally positioned for engagement by the bunter when its movement is arrested by the center fork, a lock for positively holding the knock-off plunger in an inoperative position following loom stoppage, and a trip for the lock actuated on the first beat-up movement 50 of the lay after loom stoppage to free the knock-off plunger for movement to operative position.

9. In a center fork stop motion for looms, 55 the combination of the lay, a bunter mounted on the lay for movement lengthwise thereof, an under or cam shaft having a cam, connections between the cam and bunter for moving the bunter lengthwise of the lay in one direction, a spring for moving the bunter lengthwise of the lay in the opposite direction, a center fork for arresting movement 60 of the bunter in response to the spring when the center fork detects failure of filling, a knock-off plunger for engagement by the bunter on the beat-up, a lock for positively holding the knock-off plunger in an inoperative 65 position relative to the bunter after the

plunger has caused loom stoppage, and a trip for freeing the plunger for movement to operative position on the first beat-up following the loom stoppage.

10. In a center fork stop motion for looms, 70 the combination of the lay, a knock-off plunger mounted in front of the lay, a bunter mounted on the lay, a cam for moving the bunter in one direction past the end of the knock-off plunger, a spring for moving the bunter in the opposite direction, a center fork, means controlled by the center fork for arresting movement of the bunter responsive to the spring for engagement with the knock-off plunger on detection of filling failure, a lock for holding the knock-off plunger in an inoperative position when it has been moved by the bunter to effect loom stoppage, and a trip for the lock which is actuated on the first beat up following loom stoppage. 80

11. In a center fork stop motion for looms, 90 the combination of the lay, a knock-off plunger mounted in front of the lay, a bunter and center fork mounted on the lay, means controlled by the center fork to position the bunter for engagement with the knock-off plunger on detection of filling failure to thereby stop the loom, a lock for holding the knock-off plunger in an inoperative position upon loom stoppage by the center fork, and a trip for the lock actuated on the first beat up 95 following loom stoppage to permit the knock-off plunger to become functionally effective.

12. In a center fork stop motion for looms, 100 the combination of the lay, a center fork, a bunter mounted on the lay, means controlled by the center fork to position the bunter to effect loom stoppage on failure of filling, a knock-off plunger mounted in front of the lay, a shipper knock-off adapted to be actuated by the plunger, a locking member for the knock-off plunger for holding the plunger in an inoperative position when it has been moved to effect loom stoppage, a latch for the locking member, and a part carried by the lay for tripping the latch on the first beat-up following loom stoppage. 105

13. In a center fork stop motion for looms, 115 the combination of the lay, a center fork, a bunter mounted on the lay, means controlled by the center fork to position the bunter to effect loom stoppage on failure of filling, a knock-off plunger mounted in front of the lay, a shipper knock-off adapted to be actuated by the plunger, a slide mounted on the plunger and having a cam projection, a lever connected to the slide, a latch for holding the lever with the slide in a frontward position and the cam projection maintaining the knock-off plunger in an inoperative position, and means for tripping the latch on the first beat-up when the loom is again started. 120

In testimony whereof, I have signed my name to this specification.

VERNER LINDSJO. 130
